DESIGN FOR A HOLDER FOR NARROW FABRICS

Julian Whitehill Funke, Pelham Manor, N. Y.

Application March 17, 1943, Serial No. 109,773

Term of patent 3½ years

To all whom it may concern:

Be it known that I, Julian Whitehill Funke, a citizen of the United States, residing in the city of Pelham Manor, county of Westchester and State of New York, have invented a new, original, and ornamental Design for a Holder for Narrow Fabrics, of which the following is a specification, reference being had to the accompanying drawing, forming a part thereof.

I claim:

The ornamental design for a holder for narrow fabrics, as shown.

JULIAN WHITEHILL FUNKE.
